H. O. Murdoch
INVENTOR

WITNESS:

Victor J. Evans
ATTORNEY

UNITED STATES PATENT OFFICE.

HOMER O. MURDOCH, OF CHARLOTTE, NORTH CAROLINA.

CHART.

Application filed October 12, 1920. Serial No. 416,348.

To all whom it may concern:

Be it known that I, HOMER O. MURDOCH, a citizen of the United States, residing at Charlotte, in the county of Mecklenburg and

5 State of North Carolina, have invented new and useful Improvements in Charts, of which the following is a specification.

This invention relates to indicating charts and has for an object the provision of means 10 for keeping track of the time at which medicine is to be administered to a person, so that mistakes and confusion is avoided when more than one person is acting in the capacity of nurse.

15 Another object is the provision of an indicating chart of the above character which has associated therewith the usual physician's prescription blank, so that each prescription will have its own indicating chart 20 which is severed therefrom.

Other objects and advantageous of the invention will appear as the following description is read in connection with the accompanying drawings.

25 In the drawings:—

Figure 1 is a view of a chart shown in connection with a physician's prescription blank.

Figure 2 shows the chart separated from 30 the blank.

Figure 3 is a view of a modified form of chart.

Figure 4 is a view of a still further modified form of chart.

35 Referring to the drawings in detail, the invention as illustrated in Figure 2 is formed of a sheet of paper which is divided into spaces 10 containing indicia for indicating the various days of the week, for example, 40 S indicating Sunday, M. Monday, T., Tuesday, etc. Disposed at right angles to the spaces 10 and located beneath said spaces are columns 11, two of such columns being provided for each space 10. The columns 45 contain vertical rows of numbers from 1 to 12 which are designed to represent the hours of a day. One column beneath each space is provided at its top with the letters A. M. to indicate anti-meridian, while the top of

50 the other column of each space contains the letters P. M. to indicate post-meridian. The columns of numbers located under A. M. is of a color to distinguish it from the numbers beneath P. M., so that morning and 55 evening may be readily distinguished.

The columns 11 are interrupted to provide a blank space 12 at the lower end of the chart for the insertion of indicia to distinguish the fractional parts of an hour.

In the use of the chart, should the physician prescribe the medicine to be administered every two hours and the first dose given at 10 o'clock A. M., Sunday, the numbers 10 and 11 will be crossed out, so that any person consulting the chart will readily 60 see that the next dose is to be administered at 12 o'clock. This method of crossing out the numbers will be followed throughout the use of the chart so that the next uncrossed number will be the time for administering 65 the next dose of medicine. Should the time be 10:30 or 10:45, 30 or 45 may be written in the space 12 provided for minutes and the nurse or other person administering the dose 70 may readily determine the correct time. 75

In Figure 1 the chart is shown in connection with a physician's prescription blank which is indicated at 13. The chart in all other respects is similar to that described in Figure 2, while a perforated line 14 separates the prescription blank and chart so that they may be separated. When made into pad or tablet form, the chart forms a convenient rest for the hand of the physician when writing the prescription. In Figure 80 3 there is illustrated an exceedingly simple form of the invention. In this form the spaces for containing the indications for the days of the week are shown at 15 and contain the first letters of each day as explained in 85 connection with the preceding form of the invention. Vertical columns 16 are provided beneath each space 15 by means of spaced vertical lines 17. The columns 16 are divided by horizontally disposed lines 18 so 90 as to define separate spaces which extend both vertically and horizontally beneath each of the spaces 15. To the extreme left of the chart a relatively large space 19 is provided. This space is in horizontal alignment with 95 the spaces provided by the lines 18 and contains the word "Date". When using this form of the chart the time at which the dose of medicine is due, or should be given, is indicated within the blank spaces provided beneath the indications of the days of the week. 100

In Figure 4 the chart shown consists of horizontally and vertically arranged lines which provide spaces 20, a vertical row of relatively large spaces 21 being formed along 110

the left hand edge of the chart. The top-most space contains the name "Date" and the spaces 20 in horizontal alignment with this word are adapted to have written therein the 5 days of the month. Each of the spaces 21 beneath the word "Date" contains the word "Due" and the hour at which the medicine is due may be written in the spaces 20 beneath the dates.

10 While the invention is shown and described for the use of keeping track of the time for prescribing medicine, it is useful for many other purposes and it is therefore not the purpose of the present application to restrict the invention to this particular use.

15 The invention is susceptible of various changes in its form, proportions and minor details of construction and the right in here-
20 in reserved to make such changes as proper-

ly fall within the scope of the appended claim.

Having described the invention what is claimed is:—

An indicating chart comprising a sheet 25 scored to provide vertical spaces having indicia at the top indicating the days of the week, said spaces being further divided to provide vertical spaces having indicia at the top indicating anti-meridian and post- 30 meridian and each of the last mentioned spaces having numbers from 1 to 12 indicating divisions of a day and a relatively wide blank space beneath the numbers upon which fractional parts of an hour may be written, 35 in combination with a physician's prescription blank and a line of perforations separating the chart and blank.

In testimony whereof I affix my signature.
HOMER O. MURDOCH.
